UNITED STATES PATENT OFFICE.

KLAAS KUIJPER AND HERMAN BAKKER, OF IJMUIDEN, NETHERLANDS.

FISHING NET FOR STEAM TRAWLERS.

Application filed July 30, 1921. Serial No. 488,631.

(GRANTED UNDER THE PROVISIONS OF THE ACT OF MARCH 3, 1921, 41 STAT. L. 1313.)

To all whom it may concern:

Be it known that we, KLAAS KUIJPER and HERMAN BAKKER, subjects of the Queen of the Netherlands, both residing at IJmuiden, the Netherlands, have invented certain new and useful Improvements in and Relating to Fishing Nets for Steam Trawlers (for which we have filed applications in the Netherlands, April 22nd, 1915, granted February 14th, 1919; Great Britain, granted and filed Feb. 26th, 1919; Sweden, granted and filed December 30th, 1919; Belgium, granted and filed January 9th, 1920; Spain, January 9th, 1920, granted May 26th, 1920; Portugal, January 22nd, 1920, granted February 3rd, 1921; Germany, March 7th, 1921, granted March 8th, 1921; France, granted and filed March 14th, 1921; Norway, December 30th, 1919; and Denmark, January 6th, 1920), of which the following is a specification.

This invention relates to fishing nets for steam trawlers.

Such nets, as is well known, are composed of an upper and a lower part, called the "back" and "belly" respectively, which are knotted together. The upper part as well as the lower part are composed of a trapezoidal middle piece, to one end of which the wings are secured and to the other the cod and the pockets. The trapezoidal middle piece is handknitted and in order to obtain this trapezoidal shape half a mesh is dropped at the sides in each row while knitting the piece. A net made in this way, however, possesses this disadvantage, that when dragging the net through the water it will not assume a globular shape, but is stretched and elongated with the result that the net, while being dragged through the water, offers a great resistance to the same, which greatly affects the speed of travel of the trawler.

This invention now has for its object to provide an improved net for steam trawlers in which the above stated disadvantage is eliminated. With this object in view the trapezoidal middle piece mentioned above, is not made in one piece, but is divided into a plurality of sections all of which are rectangular, the number of meshes counted crossways in the different sections being different, but is the same in all sections when counted vertically. These separate sections

are knotted together, since, however, the preceding section has a greater number of meshes counted crossways than the succeeding section, it is necessary to decrease the width of the net, this however, need not be done at the sides, but may be effected at several points at regular intervals in the centre, or in other words, two meshes of the preceding section are joined to one mesh of the succeeding section. A net made in this manner retains its globular shape while being dragged through the water, which is apparently due to the regular manner in which the width is decreased thus offering less resistance to the water and consequently increasing the speed of the trawler.

A further advantage is that the greater portion of the net can be manufactured quite simply by mechanical means, as the rectangular sections can easily be made by machine.

The knotting together of the different sections and the knotting together of the upper and lower parts of the trawl must however, be done by hand.

One form of carrying this invention into effect is illustrated by way of example in the accompanying drawing in which,

Fig. 1 represents a portion of the net showing two of the aforementioned sections knotted together,

Fig. 2 shows the upper part or back of the trawl, and

Fig. 3 the lower part or belly of the same.

In Fig. 2, showing the upper part of the net, the trapezoidal middle piece is divided into a plurality of separate sections some of them being distinguished by the reference numerals: 1, 2, 3, 4, 5 and 6. These sections originally are of rectangular shape, the first section having for instance 293 meshes counted crossways and 22 meshes counted from top to bottom, i. e., vertically. Section 2 has 280 meshes counted crossways and 22 meshes counted vertically, whereas section 3 has 260 meshes counted crossways and 22 counted from top to bottom, and so on, the width of the successive sections decreasing by a few meshes in each case so that the lowest section has for instance 60 meshes counted crossways. The vertical dimensions or depth of the different sections may be the same throughout, they may however be varied, as is for instance the case in

- sections 5 and 6, which in this particular example contain 45 rows of meshes counted from top to bottom. 7 and 8 indicate the wings, 9 the pockets and 10 the cod.
- 5 The lower part or belly of the trawl is shown in Fig. 3 and is made in the same way as the upper part, only that the middle piece is made shorter. The upper and lower parts are knotted together at the sides.
- 10 Fig. 1 shows the manner in which the aforesaid sections, i. e., two, may be knotted together and also how the net is decreased in width. 11, 12 and 13 indicate the knots, which join the sections together, whereas at 15 14, 15 and 16 it is shown how two meshes of the larger, i. e., wider section are joined to one mesh of the smaller, i. e., narrower section. This decrease of width is distributed over the whole breadth of the section and in the example shown this is done at every sixth mesh of the upper section so that in each case seven meshes of the lower and wider section are joined to six meshes of the upper and narrower section.
- 20

The distance between the points where 25 the width is contracted depends on the difference in the number of meshes counted crossways in the two respective sections and the width of the upper section.

What we claim as our invention and desire to secure by Letters Patent is:

An improved fishing net for steam trawlers having a trapezoidal middle piece which is formed of a plurality of rectangular sections, of which every succeeding section has 35 a certain number of meshes less than the preceding section, when counting crossways, the decrease in width of the net obtained on joining the different sections together being distributed over equidistant points 40 throughout the whole width of the net substantially as described.

In testimony whereof we have affixed our signatures.

KLAAS KUILPER.
HERMAN BAKKER.
